APPARATUS FOR FASTENING STEEL PAIL TOPS.

FILED JAN. 5, 1922.

2 SHEETS - SHEET 2.

UNITED STATES PATENT OFFICE.

SMITH MADISON JOHNSON, OF MIDDLEFIELD, OHIO.

APPARATUS FOR FASTENING STEEL PAIL TOPS.

Application filed January 5, 1922. Serial No. 527,192.

To all whom it may concern:

Be it known that I, SMITH MADISON JOHNSON, a citizen of the United States, and a resident of Middlefield, in the county 5 of Geauga and State of Ohio, have invented certain new and useful Improvements in Apparatus for Fastening Steel Pail Tops, of which the following is a specification.

My invention relates to improvements in 10 devices for fastening steel pail tops, and it consists in the constructions, combinations and mode of operation herein described and claimed.

One of the objects of the invention is to 15 provide an apparatus for the purpose described, including a base plate on which crimping jaws are mounted, and embodying means for holding the plate up so that the crimping edges of the jaws will come no 20 lower than the edges of the lugs which are to be crimped under.

A further object of the invention is to provide an apparatus for the purpose described, of such an arrangement that it can 25 be set upon a pail and all of the lugs of the lid crimped under in one operation.

Other objects and advantages will appear in the following specification, reference being had to the accompanying drawings, in 30 which:—

Fig. 1 is a plan view of the improved crimping apparatus,

Fig. 2 is a cross section taken substantially on the line 2—2 of Fig. 1,

Fig. 3 is a section similar to Fig. 2 but showing the crimping jaws in the final position,

Fig. 4 is a somewhat enlarged section of a portion of Fig. 3, and

Fig. 5 is a detail perspective view of one of the crimping jaws and the bracket on which it is mounted.

The construction comprises a base plate 1 with a standard 2 in the middle. The 45 handle 3, sleeve 4 and circular flange 5 slide up and down on the standard. A number of rods 6 radiate from the flange 5 to which they are suitably connected by couplings 7 which include means 8 for the adjustment 50 of the radius rods. This means comprises the threaded ends of the rods and the jam nuts which hold the position after adjustment.

The lower ends of the radius rods are 55 bent at right angles to fit into holes in the upper ends of the arms 9 of the crimping

jaws 10. The bent ends are held in place by cotter pins. The crimping jaws are pivoted at 11 to brackets 12 which are fastened on top of the base plate 1. The 60 ends of the brackets are bent over the edge of the base plate so as to provide a pendent mounting for the crimping jaws. It is to be observed that the pivotal point 11 is close to the jaws themselves. 65

The jaws extend on each side of the arm 9 so as to provide a sufficiently wide surface to insure an adequate contact with the lugs 13 of the cover C. The purpose of the invention is to bend the lugs 13 under 70 the rim 14.

Each of a plurality of brackets 15 on the base plate 1, carries a pin 16 which extends down through the base plate and is fastened to a ring 17. A spring 18 is fitted on each 75 pin 16 between the top of the bracket 15 and a pin or washer 19 which is fitted across each pin slightly above the base plate 1.

The purpose of the springs 18 is to hold the base plate 1 up, and as a consequence, 80 hold the crimping jaws 10 up so that they will come no lower than the edges of the lugs 13, as shown in Fig. 2. Were the crimping jaws permitted to come lower than the edges of the lugs, it can be readily seen that 85 the crimping operation would be impaired. The provision of the springs 18 in the particular combination disclosed, is one of the important features of the invention. 90

The operation.

The apparatus normally assumes the position illustrated in Fig. 2. It is set down upon the cover C when it is desired to turn or crimp the lugs 13. It is required to exercise reasonable care to see that the crimping jaws 10 fit the lugs. The springs 18 hold the crimping jaws 10 up so that they can move no farther than the edges of the lugs 13. 95

Having gotten the apparatus in the proper position, the operator bears down on the handle 3, whereupon the handle, sleeve 4 and circular flange 5 slide down on the standard 2, spreading the radius rods 105 6 outwardly and turning the arms 9 on their pivots 11. The downward pressure serves to force the cover C upon the pail rim 14 so that the usual rubber gasket is compressed from its normal round shape (Fig. 110 2) to the final crescent shape (Fig. 3). The same downward pressure causes the

edges of the lugs to be crimped under the rim 14 as clearly shown in Fig. 4. In removing the apparatus from the pail, the arms 9 return to the erect positions shown in Fig. 2, this by virtue of the pull on the handle 3 in lifting the device off.

Mention should be made of the fact that a portion of the inner surface of each crimping jaw 10 (Fig. 5) has a concaved surface 10 which enables fitting the lug 13 around the rim 14 more closely than would be possible were the contacting edge of the jaw 10 straight.

I claim: —

15 1. Apparatus for fastening pail covers comprising a plate, jaws carried by said plate for bending cover lugs, and means exerting a force between said plate and the cover for normally holding the apparatus in position above the rim of the cover and keep the jaws from taking a position beyond the edges of the lugs.

20 2. Apparatus for fastening pail covers comprising an element to be set upon a cover, means carried by said element to engage the cover lugs, and means having a foundation on the cover for holding said element and consequently said means in a predetermined position in respect to the 30 lugs.

25 3. Apparatus for fastening pail covers comprising a plate with a standard, brackets on which crimping jaws are pivoted, a handle slideable on the standard and having 35 connection to said jaws enabling turning all on their pivots by moving the handle; and means for holding the plate up in respect to a cover to keep the jaws from slipping beyond the edges of lugs to be crimped.

40 4. Apparatus for fastening pail covers comprising a base plate with a standard, a handle slideable on the standard, with connections to a plurality of crimping jaws which are pivoted to brackets on the base 45 plate; a ring with pins extending through the base plate, brackets on the plate receiving the upper ends of the pins, and a spring on each pin between the brackets and a washer on the pins.

50 5. Apparatus for fastening pail covers comprising a plate, jaws carried by said plate for bending cover lugs, means exerting a force between said plate and the cover for

normally holding the apparatus in position above the rim of the cover and keep the 55 jaws from taking a position beyond the edges of the lugs, and means for performing the crimping operation simultaneously depressing the plate against said rim in opposition to said force and moving the jaws 60 under the lugs.

6. Apparatus for fastening pail covers comprising a plate, jaws carried by said plate for bending cover lugs, means exerting a force between said plate and the cover for 65 normally holding the apparatus in position above the rim of the cover and keep the jaws from taking a position beyond the edges of the lugs, and means carried by the plate by which a crimping operation is performed 70 adapted to simultaneously depress the plate into contact with said cover rim in opposition to said force and causing the jaws to turn the lugs under.

7. Apparatus for fastening pail covers 75 comprising means to rest upon a cover, a plate, jaws carried by said plate for bending cover lugs, means using said resting means as a base to exert a force on the plate to normally hold it above the rim of the cover and 80 keep the jaws from taking a position beyond the edges of the lugs, and means carried by the plate and having connections to the jaws adapted to simultaneously depress said plate against the cover rim in opposition to said 85 force and cause the jaws to turn the lugs under.

8. Apparatus for fastening pail covers comprising means to rest upon a cover, a plate, means carried by said resting means 90 extending through the plate, means carried by the plate through which said extending means also pass, means exerting a force between said extending means and said plate-carried means to normally keep the plate 95 above the rim of the cover, jaws pivotally mounted on the plate and kept from taking a position beyond the edges of cover lugs by virtue of said position of the plate, and means carried by the plate having connections to the jaws to simultaneously depress the plate into contact with the cover rim in opposition to said force and move the jaws on their pivots to turn the lugs under.

100 SMITH MADISON JOHNSON.
